CLAIM

The ornamental design for an ice bath tub as shown and described.

DESCRIPTION

FIG. 1 is a top, front and right side perspective view of an ice bath tub, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the ice bath tub shown in FIG. 1.

The broken lines in the drawings depict portions of the ice bath tub that form no part of the claimed design.
